[57] CLAIM

The ornamental design for a fishing lure attachment, as
shown and described.

DESCRIPTION

FIG. 1 is a perspective view of a fishing lure attachment
showing my new design;

FIG. 2 is a left side elevational view thereof;

FIG. 3 is a top plan view thereof;

FIG. 4 is a right side elevational view thereof;

FIG. 5 is a bottom plan view thereof;

FIG. 6 is a front elevational view thereof;

FIG. 7 is a rear elevational view thereof;

FIG. 8 is a perspective view of a second embodiment;

FIG. 9 is a left side elevational view thereof;

FIG. 10 is a top plan view thereof;

FIG. 11 is a bottom plan view thereof;

FIG. 12 is a front elevational view thereof; and,

FIG. 13 is a rear elevational view thereof.

The broken line showing of a lure in FIGS. 1 and 8 is
for illustrative purposes only and forms no part of
claimed design.
